United States Patent Office

Des. 201,125
Patented May 18, 1965

201,125

RESTAURANT

Edward J. von Gund, 3600 Wilshire Blvd.,
Bradbury, Calif.

Filed May 8, 1964, Ser. No. 79,896

Term of patent 14 years

(Cl. D13—1)

FIG.-1

FIG. -3

FIG. 1 is a side elevational view of a restaurant, showing my new design;

FIG. 2 is a front elevational view of a restaurant, showing my new design; and

FIG. 3 is a perspective view.

The rear and other side of the restaurant not shown are the same in appearance as the front and side shown in FIG. 3.

I claim:

The ornamental design for a restaurant, as shown and described.
